CLAIM

The ornamental design for a pet feeding device, as shown and described.

DESCRIPTION

FIG. 1 is a front, left, top perspective view of a pet feeding device showing our new design;

FIG. 2 is a rear, right, bottom perspective view of the pet feeding device shown in FIG. 1;

FIG. 3 is a front elevational view of the pet feeding device shown in FIG. 1;

FIG. 4 is a rear elevational view of the pet feeding device shown in FIG. 1;

FIG. 5 is a left-side elevational view of the pet feeding device shown in FIG. 1;

FIG. 6 is a right-side elevational view of the pet feeding device shown in FIG. 1;

FIG. 7 is a top plan view of the pet feeding device shown in FIG. 1; and,

FIG. 8 is a bottom plan view of the pet feeding device shown in FIG. 1.

The broken lines immediately adjacent the shaded areas represent the bounds of the claimed design while all other broken lines are directed to environment and are for illustrative purposes only; the broken lines form no part of the claimed design.
